UNITED STATES PATENT OFFICE.

EMIL BÄCHLE, OF MERIDEN, CONNECTICUT, ASSIGNOR TO INTERNATIONAL SILVER COMPANY, OF JERSEY CITY, NEW JERSEY, A CORPORATION OF NEW JERSEY.

DESIGN FOR A HANDLE FOR RECEPTACLES.

SPECIFICATION forming part of Design No. 36,452, dated July 21, 1903.

Application filed June 24, 1903. Serial No. 162,968. Term of patent 3½ years.

To all whom it may concern:

Be it known that I, EMIL BÄCHLE, a subject of the Emperor of Germany, and a resident of Meriden, in the county of New Haven and State of Connecticut, have invented a new, original, and ornamental Design for Handles for Receptacles, of which the following is a brief specification, reference being had to the accompanying drawings, forming part thereof, for the special and distinguishing features of the design, and in which—

Figure 1 is a perspective view of the han-

dle embodying my new design. Fig. 2 is a view in section through the handle, showing the ornamentation of the base.

What I claim as new, and desire to secure by Letters Patent, is—

The ornamental design for the handle for receptacles, as shown.

EMIL BÄCHLE.
